UNITED STATES PATENT OFFICE.

ARTHUR LEYTHAM, OF NEWARK, NEW JERSEY, ASSIGNOR TO SPLITDORF ELECTRICAL COMPANY, OF NEWARK, NEW JERSEY.

LAMP SOCKET.

Application filed September 29, 1925. Serial No. 59,255.

This invention relates to a lamp socket and as illustrated in the drawing is especially adapted to be used for illuminating purposes in a radio receiving set such as 5 described in application of George L. Lang, Serial No. 31,466 filed May 19, 1925. In such a radio set as disclosed in said Lang application it is proposed to illuminate the dials from the interior of the set so that 10 the numbers or indicia on the dials may be plainly discernible by an observer when the room, in which the set is placed, is darkened.

The object of my invention is to provide 15 a lamp socket which is rotatable about its support member or members so that the lamp may be swung to any position to give the proper illumination.

Another object of my invention is to provide 20 a socket of the character herein described which will be cheap to construct yet efficient in its operation.

My invention will be clearly understood 25 by a reading of the following specification taken in connection with the annexed drawing in which,

Figure 1 is a view of the socket and support members with the socket pointed toward the observer.

Figure 2 is a view similar to Fig. 1, but 30 with the socket rotated at an angle 90° whereby the lamp is pointed downward.

In the drawing, 1 is a shell adapted to receive a lamp preferably of the miniature type. 2 is the central contact of the lamp insulated by an insulator 3 from the shell 1. The shell is supported by a pair of arms 4 and 5 which are oppositely formed so as to engage the shell 1. These arms are attached to the shell in any satisfactory manner as 35 by soldering. The other ends of the arms 4 and 5 are bent at 6 and 7 preferably in opposite directions so as to provide means for pivotally mounting the arms to suitable support members. The ends 6 and 7 are also 40 preferably parallel with each other.

Support members 8 and 9 are provided and these are preferably constructed of strong insulating material and have holes 45 10 for fastening to some other member. The 50 ends of the arms 8 and 9 are provided with metallic clips 11 and 12, the same being fastened together by any suitable means such as rivets 13. Clips 12 are provided

with outwardly bent lugs 14 that engage the ends 6 and 7 of the arms 4 and 5. The connection between the lugs 14 and the arms 6 and 7 is preferably made with a rivet or eyelet 15 thereby providing a pivotal joint so that the socket may be rotated thereabout in order that the lamp carried in the socket 55 may be set at any desired angle. Since the socket is pivotally carried by the support members 8 and 9, these members may be set at any angle and not in the same plane as illustrated in the drawing; furthermore, in 60 some cases one of the support members and the associated arm may be dispensed with, and while I have shown one form of carrying my invention into practise, I do not wish to be limited to the precise details illustrated. 65

Having thus described my invention what I claim is:

1. A lamp socket comprising; a shell to receive a lamp, a pair of arms having an 75 end of each bent around said shell in opposite directions and fastened thereto, said arms having their opposite ends bent so as to be substantially parallel, a pair of support members having ends adapted to be attached to said arms and pivotal means connecting said support ends and said arms.

2. A lamp socket comprising; a shell to receive a lamp, a pair of arms having an 85 end of each bent around said shell in opposite directions and fastened thereto, said arms having their opposite ends bent in opposite directions but substantially parallel, a pair of support members having ends adapted to be attached to said arms and pivotal means connecting said support ends and said arms. 90

3. A lamp socket comprising; a shell to receive a lamp, a pair of arms having an end of each bent around said shell in opposite 95 directions and fastened thereto, said arms having their opposite ends bent so as to be substantially parallel, a pair of support members of insulating material, metallic clips attached to the ends of said support members, said clips having lugs to cooperate with a pair of said arm ends and pivotal means joining said lugs and arm ends. 100

In testimony whereof, I affix my signature.

ARTHUR LEYTHAM.
